UNITED STATES PATENT OFFICE

EDWARD E. LITKENHOUS, OF LOUISVILLE, KENTUCKY

HAIRPIN

Application filed August 17, 1931. Serial No. 557,457.

My invention relates to improvements in hairpins, and has for its object to provide a hairpin having a construction such as to hold the hair in place effectively and at the same time hold the hairpin itself in the position in which it has been fixed, without creeping or slipping.

More specifically it is the object of my invention to provide a hairpin wherein the two shanks shall have corrugation or multiple bends which are in single planes on each shank, but which planes are angularly disposed toward one another so as to intersect in a line at one side of the hairpin but in the central plane which divides and is perpendicular to the plane of the shank margins.

It is a further object of my invention to provide on at least one of the shanks or tines a double crimped loop extending longitudinally along the length of said shank so as to provide a pair of crimped holding members straddling with their crimps or loops a longitudinally extending portion of wire corresponding to the upper part of the shank or tine.

In the drawings, illustrating one form of my invention,—Fig. 1 is a side plan view of a hairpin embodying the features of my invention. Fig. 2 is an edge view corresponding to the view of Fig. 1. Fig. 3 is a top plan view of my invention.

As illustrated my hairpin comprises in effect a loop formed with a top bow 10, and depending shanks 11 and 12. Each of shanks 11 and 12 is provided with a multiplicity of bends or corrugations, those of shank 11 being designated 13 and those of shank 12 as 14. The corrugations 13 are all in a common plane, and the corrugations 14 are in a common plane, but the two planes are angularly disposed as clearly shown in Fig. 3.

The effect of thus disposing these bends is to cause the shanks not only to hold in the hair but to tend to draw together as the hairpin is inserted in the hair, thus making the grip on the hair considerably more secure than it otherwise would be.

The top loop 10 is not continuous, but, as clearly shown, runs into a long depending loop, having side shanks 16 and 17, shank

16 being continuous with top loop 10, and shank 17 connecting through another top loop 18 with the tine 19 of shank 12.

The shanks 16 and 17 embrace or straddle the tine 19 and are formed with corrugations or crimped portions 20 extending in planes perpendicular to the plane of shanks 11 and 12. The effect of this arrangement is that when the hairpin is inserted in the hair it (the hair) is held bent in opposite directions and grips it firmly thus preventing slipping.

The advantages of my invention will be apparent from the foregoing description. The hairpins embodying the invention can be manufactured from wire in the manner employed for making ordinary hairpins. Yet the arrangement of crimping of the shanks, and the provision of the extra crimped top loop with sides embracing the tine of one of the shanks makes a hair-gripping and retaining construction in a high degree effective for holding the hair.

I claim:

1. A hairpin having a shank thereof crimped to form a multiplicity of bends, all said bends lying in a common plane which is disposed at an angle to the plane of the shanks.

2. A hairpin having its two shanks crimped to form on each shank a multiplicity of bends, all the bends of each shank lying in planes each disposed at an angle to the plane of the shanks.

3. A hairpin having its two shanks crimped to form on each shank a multiplicity of bends, all the bends of each shank lying in planes each disposed at an angle to the plane of the shanks, the planes of said bends intersecting in a plane on the median line and perpendicular to the plane of the shanks.

4. A hairpin having a shank thereof crimped to form a multiplicity of bends, all said bends lying in a common plane which is disposed at an angle to the plane of the shanks, and an elongated loop adjacent and having its sides straddling the tine of the upper part of one shank.

5. A hairpin having its two shanks crimped to form on each shank a multiplicity of bends, all the bends of each shank

lying in planes each disposed at an angle to the plane of the shanks, and an elongated loop adjacent and having its sides straddling the tine of the upper part of one shank.

5 6. A hairpin comprising a pair of substantially parallel shanks, and an elongated loop at the top having tines on either side of and substantially parallel with the tine of the upper part of one shank.

10 7. A hairpin comprising a pair of substantially parallel shanks, and an elongated loop at the top having tines on either side of and substantially parallel with the tine of the upper part of one shank, said loop tines being 15 crimped so as to form bends extending across the plane of the shanks and on both sides of said loop tine.

EDWARD E. LITKENHOUS.
